UNITED STATES PATENT OFFICE.

EDWARD A. RUPERT, OF ABERDEEN, WASHINGTON.

LOCK.

1,191,347.

Specification of Letters Patent. Patented July 18, 1916.

Application filed July 28, 1915. Serial No. 42,366.

To all whom it may concern:

Be it known that I, EDWARD A. RUPERT, a citizen of the United States, residing at Aberdeen, in the county of Grays Harbor 5 and State of Washington, have invented a new and useful Lock, of which the following is a specification.

This invention relates to locks especially designed for use in connection with film 10 boxes, although it is to be understood that the same can also be used to advantage in connection with different kinds of cases.

One of the objects of the invention is to provide means whereby it becomes impossible to open more than one door in a box or 15 casing at one time, the opening of one door operating to prevent the unlocking of the other door or doors of the box or case so that before another door can be opened, it 20 is necessary to have all of the doors closed.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, can be made within the scope of what is claimed, without departing from the spirit of the invention. 30

In the accompanying drawings the preferred form of the invention has been shown.

25 In said drawings:—Figure 1 is a perspective view of a portion of a box having the present improvements combined therewith, one of the doors of the box being shown open and the other closed. Fig. 2 is a vertical longitudinal section through a portion of a box and through the open door thereof. Fig. 3 is an enlarged vertical longitudinal section through the locking bolt and adjacent parts. Fig. 4 is an enlarged view 40 partly in section and partly in elevation of the locking bolt and adjacent parts, the same showing the relative positions when the door is closed. Fig. 5 is a view showing diagrammatically the electric circuit 45 partly in section and partly in elevation of the locking bolt and adjacent parts, the same showing the relative positions when the door is closed. Fig. 5 is a view showing diagrammatically the electric circuit 50 forming a part of the locking system.

Referring to the figures by characters of reference 1 designates a box or casing which, in the present instance, has two sliding doors indicated at 2 and 3 respectively. 55 Each door has a rearwardly extending lip 4 at its lower end adapted, when the door is

closed, to press upwardly against or close to the bottom of the case, as shown for example in Fig. 4. Arranged in the bottom portion of the case is a solenoid 5 the armature 6 of which is normally pressed outwardly by a spring 7, this armature being guided within a forwardly projecting tubular core 8 which extends close to the path of the door to be fastened. The armature 6 has a locking bolt 9 connected thereto, said bolt having an enlargement 10 guided within the projecting tubular portion 8, the outer end of the bolt being normally pressed by spring 7 against the back face of the door 70 to be secured. The door has a recess 11 in the lower portion thereof adapted to receive the projecting end of bolt 9 when the door is in closed position, so that the door is thus secured against opening. The solenoid 75 is provided with normally spaced spring contact strips 12 and 13, the strip 13 having a button 14 projecting downwardly therefrom beyond the bottom of the case or box 1 so that, when the door is moved upwardly 80 to closed position, the lip 4 thereon will press against the contact strip 12, thus completing the circuit to push buttons 15 so that when either or any of these buttons are pressed, the circuit will be closed through 85 its respective solenoid, attracting the armature and unlocking the door.

Arranged above each of the doors within the case or box 1 is a push button 15.

The arrangement of the wiring used in 90 connection with the locking apparatus has been shown diagrammatically in Fig. 5. It will be seen that the contact strip 13 of one solenoid is connected by a wire 16 to the source of energy indicated at 17, while 95 the contact 12 of said solenoid is electrically connected to the contact 13 of the next adjoining solenoid. The contact 12 of the second solenoid is electrically connected to one contact of each of the buttons 15, while 100 the other contacts of the buttons 15 are electrically connected to the respective solenoids. These solenoids are in turn connected to the battery or other source of energy indicated at 17. 105

From the foregoing description it will be apparent that when the solenoids are de-energized, the bolts 9 are pressed forwardly by springs 7 into the respective recesses 11, thus securing the doors in closed positions. 110 When the doors are in closed positions, the two contacts 13 are pressed against the re-

spective contacts 12. When it is desired to open one of the doors, the button 15 thereabove is depressed so as to complete the circuit to the solenoid belonging to said door, 5 whereupon the energized solenoid will retract the bolt from said door and allow the door to be lowered. Thus the circuit will be broken between the contacts 12 and 13 provided for the opened door and, consequently, the circuit will be broken through 10 both solenoids so that no matter which of the buttons 15 may be depressed, it will be impossible to energize either solenoid until the opened door has been closed, thus to close 15 the circuit through its contacts 12 and 13.

Obviously by providing a plurality of doors, the same arrangement may be carried out, it merely being necessary to arrange the contacts 12 and 13 in series as shown in Fig. 20 5 so that by the breaking of the electrical connections between any two of the contacts, all of the solenoids are rendered inactive.

As before pointed out, while the improvements herein described are especially useful in connection with film boxes, they can be used in connection with any kind of filing 25 cases and the like.

What is claimed is:—

1. The combination with a case having 30 separate doors, magnets adjacent the doors, a source of electrical energy, and means controlled by each door, when closed, for maintaining the electrical connections between said magnets and the source of electrical 35 energy, of buttons for completing the circuits through the respective magnets when the doors are closed, and door engaging bolts movable with and projecting beyond the end of the armature of each magnet, said 40 bolts being normally projected to door engaging positions.

2. The combination with a case having separate doors, a magnet adjacent each door, and a door engaging bolt movable with and 45 projecting beyond the end of the armature of each magnet, of a source of energy, separate pairs of contacts disposed in series in

the circuit with the magnets and source of energy, a circuit closer for each magnet, and means upon each door for closing the 50 contact of its respective pair of contacts to maintain the circuits closed through said contacts when the doors are closed.

3. The combination with a case having a plurality of doors, of a magnet for each 55 door, a bolt movable with and projecting beyond the end of the armature of each magnet, means for holding the bolt normally pressed into engagement with the respective doors, a source of electrical energy 60 in circuit with the magnets, normally open circuit closers provided for the respective magnets, and separate pairs of contacts in circuit with the magnets and normally held together by the doors when closed, said 65 contacts being adapted to break the circuits to all of the magnets when one of the doors is opened.

4. The combination with a case and doors 70 movably connected thereto, of a magnet adjacent each door, a locking bolt movable with and projecting beyond the end of the armature of each magnet, yielding means for holding each bolt normally in engagement with the adjacent door, a source of 75 electrical energy in circuit with the magnets, a separate pair of contacts adjacent each door, one of said contacts being yieldingly supported normally out of engagement with the other contact of the pair, means upon 80 each door for engaging the adjacent yieldingly supported contact to hold it against the opposed contact when the door is closed, and a normally open circuit closer for each 85 magnet adjacent to the door controlled by the magnet.

In testimony that I claim the foregoing as my own, I have hereto affixed my signature in the presence of two witnesses.

EDWARD A. RUPERT.
